US0D1097121S

(12) **United States Design Patent** (10) **Patent No.:** **US D1,097,121 S**
(45) **Date of Patent:** **** Oct. 7, 2025**

(54) **INHALER**

(71) Applicant: **SUZHOU SINGMED MEDICAL DEVICE SCIENCE AND TECHNOLOGY LTD.**, Suzhou (CN)

(72) Inventors: **Fei Zhang**, Suzhou (CN); **Xiaoyuan Sun**, Suzhou (CN); **Guangtao Zhao**, Suzhou (CN)

(73) Assignee: **SUZHOU SINGMED MEDICAL DEVICE SCIENCE AND TECHNOLOGY LTD.**, Suzhou (CN)

(**) Term: **15 Years**

(21) Appl. No.: **35/520,575**

(22) Filed: **Jan. 17, 2024**

(80) **Hague Agreement Data**

Int. Filing Date: **Jan. 17, 2024**

Int. Reg. No.: **DM/236363**

Int. Reg. Date: **Jan. 17, 2024**

Int. Reg. Pub. Date: **Apr. 19, 2024**

(30) **Foreign Application Priority Data**

Nov. 14, 2023 (CN) 202330742178.3

(51) **LOC (15) Cl.** **29-02**
